UNITED STATES PATENT OFFICE.

MATTHIAS P. COONS, OF LANSINGBURG, NEW YORK.

FLEXIBLE FENCE.

Specification of Letters Patent No. 8,254, dated July 29, 1851.

To all whom it may concern:

Be it known that I, MATTHIAS P. COONS, of Lansingburg, county of Rensselaer, and State of New York, have invented a new and 5 useful improvement in a device or apparatus for the purpose of uniting the upper bars or rails of banister or picket fence or other similar device and also the same for the purpose of attaching and securing the said 10 bars or rails to a post whether the structure be of wood or other material, which I nominate "a self-graduating apparatus" as applied to fence railing or other similar device equally adapted to all the various grades 15 of elevations and depressions or undulations of soil, and also the same device admits of any and all the variations of course.

The nature of my invention consists in an improved mode of connecting, and attaching panels of banister or picket fence, or railing, to each other, and to a post; and by the same device, the said fence, or railing, may be placed, or erected, on any, and all 20 grades of undulating surface, and all 25 variations of course, the object of which is that fence, or railing may be manufactured at any manufacturing establishment all upon one, and the same principle of construction, not having any reference in its 30 construction on what grade of elevations or depressions, the fence or railing is to be placed or what variations of course, and I hereby declare, that the following is a full and exact description and operation of the 35 same.

By the use of two concave plates, of an oval or round form, the radius of the concavity and the radius of the circular form, may be determined, as the extent of either 40 is not material. The cavity of the lower plate being upward, and the cavity of the upper plate being downward, when placed together form an oval space, between them, and when compressed together, form 45 grippers or clasp, in which the bars or rails are secured. For a more particular description thereof reference may be had to the annexed drawings.

Figure 1, represents a perspective view of 50 the lower plate resting on the top of a post with a pin passing through its center as represented by letter *a*, *b*, *b* represents two short pins, at or near the edge of each end of the plate. Fig. 2 represents the upper plate 55 having a flange on each side thereof, the

spaces without the flange, the width of which is determined by the width of the rail to be used, and the width of the flanges, or rims is also determined by the thickness of the bars to be used, this plate also has 60 pins at or near the edge of each end; the pins of both the lower and upper plate exactly corresponding. Fig. 3 represents the two plates (Figs. 1 and 2) holding in its grasp a section of a bar or rail on either end thus 65 forming a clasp, and also showing that the said bars, though firmly held, by the thus formed clasp, admits of any variation of course, and also of elevation and depression. Fig. 4, represents a bar, or rail, perforated 70 with conical holes mortises or apertures being the largest at the bottom, and the smallest on the upper side of the bar. Fig. 5 represents a section of one bar, having three banisters inserted and secured in the conical 75 holes the pickets or banisters being perpendicular and the bars horizontally or inclined; thus showing that a joint may be retained by the use of tapering holes or any grade desired not exceeding angles of thirty- 80 three degrees. Fig. 6, represents two panels of fence made and constructed according to this invention. Letter *c*, represents a panel placed on the level, and letter *d*, a panel on an elevation, and also on an angle, both of 85 which are secured to each other and to the posts, by the clasp represented by Fig. 3, both of which panels, are made equally alike, as to the holes in the bars of each, are equally conical. Fig. 7, represents a clasp 90 constructed upon the same principle as that of Fig. 3, but changed in form, so as to admit, the reception of bars, at right angles; and may be so formed, as to admit in its grasp 3, or 4 bars thus forming cross fences passing 95 each other at right angles.

The cavity within the plates admits of sufficient space for the end of the bar to sway laterally sufficiently to allow the bar to be placed on any ordinary desired course or 100 elevation, and tapering mortises, holes, or apertures, in the bars, which also admits a panel of fence to be racked sufficiently, to admit of its being placed on any required ascent, or depression not exceeding 33 degrees, the banisters or pickets remaining perpendicular.

Having thus fully set forth and described the nature of my invention and its practical operation, I do not claim any particular 110

form or construction, of a post in connection therewith, the same not being essential nor whether the same be of wood or any other substance (I having heretofore invented a metal post being a convenient device to use in connection herewith) but

1. What I do claim as my invention and desire to secure by Letters Patent, is the form and construction, of the two concave plates 10 with pins near their open ends, forming one coupling-cap, or clasp, for the purpose of uniting together, the open bars of fence, or railing, whether the same be of wood or metal and also securing of the same, by the 15 use of a pin with a screw thereon, or other de-

vice, on the top of a post in the manner, and for the purpose, as herein described.

2. And in connection therewith, I claim perforating the bars, or rails, with conical, or tapering holes, mortises or orifices, for the 20 insertion of pickets or banisters in the manner, and all for the purpose, as is herein substantially set forth, and described.

Datend at Lansingburg this eighteenth day of March, 1851.

MATTHIAS P. COONS.
